US00D864157S

(12) **United States Design Patent** (10) **Patent No.:** **US D864,157 S**
Hu (45) **Date of Patent:** **** Oct. 22, 2019**

(54) **HEADPHONE**

(71) Applicant: **SHENZHEN QIANHAI PATUOXUN NETWORK AND TECHNOLOGY CO., LTD**, Shenzhen (CN)

(72) Inventor: **Zaihui Hu**, Shenzhen (CN)

(73) Assignee: **SHENZHEN QIANHAI PATUOXUN NETWORK AND TECHNOLOGY CO., LTD**, Shenzhen (CN)

(**) Term: **15 Years**

(21) Appl. No.: **29/698,081**

(22) Filed: **Jul. 15, 2019**

(51) LOC (12) Cl. **14-01**

(52) U.S. Cl.

USPC **D14/206**; D14/226

Primary Examiner — Paula Allen Greene

(57) **CLAIM**

The ornamental design for a headphone, as shown and described.

DESCRIPTION

FIG. 1 is a perspective view of a headphone showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and

FIG. 8 is a bottom plan view thereof.

FIG. 9 is an enlarge view of portion 9 shown in FIG. 1; and, FIG. 10 is an enlarge view of portion 10 shown in FIG. 1. The broken lines in the drawings depict portions of the headphone that form no part of the claimed design.

1 Claim, 10 Drawing Sheets
